US00D432208S

United States Patent

[19]

Beaver et al.

[11] Patent Number: Des. 432,208

[45] Date of Patent: ** Oct. 17, 2000

[54] SPRAYER SYSTEM

[75] Inventors: **Larry Gene Beaver**, Lake Park; **Edwin Frank Hoff, Jr.**; **Allan Steven Las**, both of Valdosta; **Edward Francis Nichenko**, Hahira; **Terrie Jo Pellitteri**, Valdosta, all of Ga.; **Mark T. MacLean-Blevins**, Westminster; **Donald Patrick Reilly**, Baltimore City, both of Md.; **Craig Stephen Ketcham**, Somerset, Pa.

[73] Assignee: **Griffin LLC**, Valdosta, Ga.

[**] Term: **14 Years**

[21] Appl. No.: **29/111,906**

[22] Filed: **Oct. 6, 1999**

[51] LOC (7) Cl. **23-01**

[52] U.S. Cl. **D23/225**

[58] Field of Search D23/213, 225; D8/1; 239/310, 312, 314, 316-8
